UNITED STATES PATENT OFFICE.

WILLIAM WESLEY CROCKER, OF JUNCTION CITY, KANSAS.

CLOTHES-STICK.

1,386,992.

Specification of Letters Patent.

Patented Aug. 9, 1921.

Application filed September 15, 1920. Serial No. 410,388.

To all whom it may concern:

Be it known that I, WILLIAM WESLEY CROCKER, a citizen of the United States, residing at Junction City, in the county of 5 Geary and State of Kansas, have invented a new and useful Clothes-Stick, of which the following is a specification.

This invention relates to clothes sticks, and it is the primary object of the invention 10 to provide means at one end of a clothes stick to prevent displacement of the clothes lifted by the stick, during the removal of the clothes from the boiler or the like.

A further object of the invention is to 15 provide a device of this character, wherein the securing means includes smooth and regular surfaces, thereby eliminating any possibility of damaging the clothes or articles, by the use of the stick.

20 With the foregoing and other objects in view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

30 Referring to the drawing:—

Figure 1 illustrates a side elevational view of a clothes stick constructed in accordance with the present invention, the same being shown partly in section to illustrate the 35 manner of securing the head to the stick, and

Fig. 2 illustrates a modified form of securing means employed in securing the head to the stick.

40 Referring to the drawing in detail, the reference character 5 designates the handle of the clothes stick which has one of its extremities tapered as at 6, the tapered portion being however reduced in diameter, as 45 compared with the handle portion 5.

The head of the stick includes a socket member 7, and a head 8, approximately spherical in general outline, and having spirally disposed ribs formed thereon, the socket 50 member 7 being of a construction to accommodate the reduced tapered portion 6 of the stick, there being provided suitable open-

ings in the socket member for receiving the pin 9, which passes through the stick in a manner to prevent displacement of the head. 55

As shown, the material between the convolutions, as indicated at 10 is rounded transversely, to eliminate the same cutting or in any manner damaging the articles being removed, it being the purpose of the invention to force the stick into contact with an article to be removed, and twist the same into the article, whereupon the article becomes wrapped around the head.

It follows that when the handle portion 65 5 is rotated in the opposite direction, the head is released from the article so that the article may be deposited in any convenient place.

With reference to Fig. 2 of the drawing, 70 the handle 5' is provided with a central bore 6' adapted to accommodate the stem 7' formed integral with the head 8', which is also convoluted, and provided with recessed portion 9', the recessed portion being designed to accommodate the flange 10' formed at one end of the handle portion 5'.

In this form of the invention, the stem 7' is provided with a suitable transversely extending opening designed to accommodate 80 the securing pin 11', which passes through the handle portion 5' and the stem 7' to secure the head 8' against movement. It might be further stated however that this form of invention absolutely insures against 85 damage to the articles to be lifted, since there are no protruding parts nor sharp edges forming a part of the present invention.

Having thus described the invention, what 90 is claimed as new is:—

In a clothes stick, a head, said head being approximately spherical in general outline, and provided with spirally disposed ribs, a socket member integral with the head, and a 95 handle having one end fixed in said socket member.

In testimony that I claim the foregoing as my own, I have hereto affixed my signature in the presence of two witnesses.

WILLIAM WESLEY CROCKER.

Witnesses:

Mrs. E. B. THOMPSON,
AMY THOMPSON.
